US0D1113720S

(12) **United States Design Patent** (10) Patent No.: **US D1,113,720 S**
(45) Date of Patent: ** Feb. 17, 2026

(54) **INVERTER POWER STATION PARALLEL KIT**

(71) Applicant: **Champion Power Equipment, Inc.**,
Santa Fe Springs, CA (US)

(72) Inventors: **Artur Starosciak**, Greendale, WI (US);
Greg Pauken, Hartland, WI (US)

(73) Assignee: **Champion Power Equipment, Inc.**,
Las Vegas, NV (US)

(**) Term: **15 Years**

(21) Appl. No.: **29/869,130**

(22) Filed: **Dec. 22, 2022**

(51) **LOC (15) Cl. 13-02**

(52) **U.S. Cl.**

USPC **D13/110**

(58) **Field of Classification Search**

CLAIM

The ornamental design for an inverter power station parallel kit as shown and described.

DESCRIPTION

FIG. 1 is an upper right front perspective view of an inverter power station parallel kit according to the present invention. FIG. 2 is a lower left rear perspective view of the inverter power station parallel kit of FIG. 1.

FIG. 3 is a front view of the inverter power station parallel kit of FIG. 1.

FIG. 4 is a rear view of the inverter power station parallel kit of FIG. 1.

FIG. 5 is a right side view of the inverter power station parallel kit of FIG. 1.

FIG. 6 is a left side view of the inverter power station parallel kit of FIG. 1.

FIG. 7 is a top view of the inverter power station parallel kit of FIG. 1.

FIG. 8 is a bottom view of the inverter power station parallel kit of FIG. 1.

FIG. 9 is an upper right front perspective view of the inverter power station parallel kit of FIG. 1, showing the design in an alternate configuration.

FIG. 10 is a lower left rear perspective view of the inverter power station parallel kit of FIG. 1, showing the design in an alternate configuration.

FIG. 11 is a front view of the inverter power station parallel kit of FIG. 1, showing the design in an alternate configuration.

FIG. 12 is a rear view of the inverter power station parallel kit of FIG. 1, showing the design in an alternate configuration.

FIG. 13 is a right side view of the inverter power station parallel kit of FIG. 1, showing the design in an alternate configuration.

FIG. 14 is a left side view of the inverter power station parallel kit of FIG. 1, showing the design in an alternate configuration.

FIG. 15 is a top view of the inverter power station parallel kit of FIG. 1, showing the design in an alternate configuration; and,

FIG. 16 is a bottom view of the inverter power station parallel kit of FIG. 1, showing the design in an alternate configuration.

The broken lines in the drawing views are included for the purpose of illustrating portions of the inverter power station parallel kit that form no part of the claimed design.

The inverter power station parallel kit is shown with a symbolic break in its length. The appearance of any portion of the article between the break lines forms no part of the claimed design.
